DESCRIPTION

FIG. 1 is a front perspective view of the sunglass of the present invention showing our new design;

FIG. 2 is a front elevational view thereof;

FIG. 3 is a rear elevational view thereof;

FIG. 4 is a side view thereof;

FIG. 5 is a top plan view thereof; and,

FIG. 6 is a bottom plan view thereof.

The broken lines in the drawings are for the purpose of illustrating portions of the sunglass that form no part of the claimed design.

1 Claim, 4 Drawing Sheets
